Nelson M. Howard

UNITED STATES PATENT OFFICE.

WALTER W. BRADBURY, OF ST. LOUIS, MISSOURI, ASSIGNOR TO UNITED SHOE MACHINERY CORPORATION, OF PATERSON, NEW JERSEY, A CORPORATION OF NEW JERSEY.

WOOD-HEEL-TURNING MACHINE.

Application filed May 28, 1927. Serial No. 195,117.

This invention relates to heel turning machines and is illustrated as embodied in a wood heel turning machine of the type disclosed in United States Letters Patent No. 1,580,184, issued April 13, 1926, on the application of John H. Vinton.

Machines of the type mentioned are provided with a jack for holding a wood heel blank and swinging it past a rotary cutter.

10 The jack comprises a base plate on which the heel seat portion of the blank rests, and a clamping member which may be swung into engagement with the toplift portion of the blank. The clamping member is made adjustable in a direction parallel to its length to permit its adequate engagement with the toplift portions of blanks of widely varying shapes and sizes, and is forced down on the blank by the end of an adjustable screw 20 mounted in the end of a clamping lever.

An object of the present invention is to provide improved clamping mechanism adapted for use in an organization of the type referred to, which mechanism will be smoother and more definite in its operation. I have accomplished this by providing a definite seat in the clamping member for engagement with the end of the screw, and a pivotal mounting for the screw which, as 20 illustrated, enables the screw end to engage the seat properly irrespective of the adjustment or of the swinging movement of the clamping member. Preferably several seats are provided to allow suitable engagement 35 without undue pivotal action of the screw.

These and other features of the invention comprising certain combinations and arrangements of parts will be apparent from the following description of a preferred embodiment of the invention shown in the drawings, in which

Fig. 1 is a side elevation of the front part of the machine; and

Fig. 2 is a sectional detail showing the 45 trunnioned screw.

In the drawing only so much of the machine is shown as is necessary for the understanding of the present invention, and reference may be made to Letters Patent No. 50 1,580,184, for further illustration and description of the construction and operation of parts not fully disclosed herein.

The frame 10 of the illustrated wood heel turning machine has a vertical cutter shaft

12 with a formed cutter head 14. The 55 frame also carries a shaft 16, parallel to the cutter shaft, on which is mounted a swinging bracket or crane 18 carrying a pivoted shaft 20 in its outer end. This shaft is moved vertically by the engagement of an arm 22 on its lower end with a pivotally adjustable so-called lower track 24, and carries at its upper end the jack holder 26. Pivotally mounted in the jack holder at 28 is the jack frame 30, having a base plate 32 arranged to 60 engage the heel-seat portion of a wood heel blank, a breast gage 34, and a toplift portion clamping member 36. The member 36 is mounted on a horizontally adjustable pivot 38 having the considerable range of adjustment necessary to enable its end to overlap and engage properly with the toplift end of any type of heel blank 39.

A clamping member 40 is pivotally mounted at 42 on the jack frame 30. This member 40 has a screw 44 mounted in its end, over the clamping member 36. When the heel blank is clamped the member 40 is forced to the position shown in Fig. 1 by mechanism to be described, and variations 80 in the thickness of the work are accommodated by adjustment of the screw up and down in the end of the member 40, so that any thickness of blank can be clamped with the member 40 in substantially the same position. The member 36 is normally held up 85 against the screw 44 by a spring 45.

In accordance with a feature of the present invention the upper surface of the member 36 is provided with a number of seats 48, formed as holes or drill spots, arranged along the length of the member 36, so that any longitudinal adjustment will bring one of these seats nearly under the screw 44. The screw 44 is threaded into a trunnion 90 piece 50, which is horizontally pivoted in the end of the clamping member 40, thus permitting the screw to swing in the vertical plane of the member 36, and to find the convenient seat 48 for any given condition. A jam nut 95 52 or any other convenient device can be used to preserve the adjustment of the screw in the trunnioned nut 50. Minor variations in height due to irregularities in a run of blanks are compensated for by a spring 100 54 mounted in seats 55, one in the end of the member 40 and the other in the middle part of a lever 56 terminally pivoted at 58 on the

member 40 and having a cam roll 60 at its other end engaging a cam 62 on a cam lever 64 pivoted at 66 on the jack frame 30.

In the drawing the jack is shown in blank-clamping position. To release the blank the operator will raise the handle 68 causing the cam 62 to run from under the roll 60. This will release the members 56, 40 completely so that they can swing around the pivot 42 releasing the member 36, when the blank can be removed and a new one inserted. The members 36, 40, the pivots 38, 42, 50 and the depression 48 constitute a linkage which changes its form as the member 36 is forced down on the heel blank 39. The pivot at 50 prevents any tendency of the end of the screw 44 to scrape over the top of the member 36 as this change in form takes place and avoids any danger of breaking or damaging the screw or the member 36. The jack as a whole is tilted around the pivot 28 by the adjustable so-called upper track 70, as will be well understood by those familiar with the art.

The mechanism for compensating for minor variations in work thickness, exemplified by the resilient compound lever 40, 56, is the invention of Norton W. Kinney and is not claimed herein.

Having described my invention, what I claim as new and desire to secure by Letters Patent of the United States is:

1. In a wood heel turning machine, a jack having a clamping face arranged to receive the heel-seat surface of a heel blank, a clamping member arranged to engage the toplift surface of the blank, a second clamping member arranged to force the first-named clamping member toward the clamping face, and a screw trunnioned in the second clamping member and engaging the first-named clamping member.

2. In a wood heel turning machine, a jack having a clamping face arranged to receive the heel-seat surface of a heel blank, a pivotally mounted clamping member arranged to engage the toplift surface of the blank, a pivotally mounted second clamping member arranged to force the first-named clamping member toward the clamping face, and a screw in the second clamping member and engaging the first-named clamping member, said screw being trunnioned in the second clamping member to take up the relative movement between the two said clamping members on their pivots.

3. In a wood heel turning machine, a jack having a clamping face arranged to receive the heel-seat surface of a heel blank, a clamping member arranged to engage the toplift surface of the blank, said clamping member being adjustable longitudinally of the heel blank, a clamping lever arranged to force the clamping member toward the clamping face, and a screw trunnioned in

the clamping lever and engaging the clamping member.

4. In a wood heel turning machine, a jack having a clamping face arranged to receive the heel-seat surface of a heel blank, a pivotally mounted clamping member arranged to engage the toplift surface of the blank, said clamping member being adjustable longitudinally of the heel blank, a clamping lever arranged to force the clamping member toward the clamping face, a screw trunnioned in the clamping lever and engaging the clamping member, and means for operating the clamping lever.

5. In a wood heel turning machine, a jack having a clamping face arranged to receive the heel-seat surface of a heel blank, a clamping member arranged to engage the toplift surface of the blank, a clamping lever arranged to force the clamping member toward the clamping face, a threaded nut trunnioned in the clamping lever, and a screw in the nut engaging the clamping member, said clamping member having a hole in its surface to receive the end of the screw.

6. In a wood heel turning machine, a jack having a clamping face arranged to receive the heel-seat surface of a heel blank, a pivotally mounted clamping member arranged to engage the toplift surface of the blank, a clamping lever arranged to force the clamping member toward the clamping face, a screw trunnioned in the clamping lever and engaging the clamping member, said second-named clamping member having a seat in its surface to receive the end of the screw, a cam roll on the clamping lever, and a cam lever arranged to co-operate with the roll to move the clamping lever.

7. In a wood heel turning machine, a jack having a clamping face arranged to receive the heel-seat surface of a heel blank, a clamping member arranged to engage the top-lift surface of the blank, said clamping member being adjustable longitudinally of the heel blank, a clamping lever arranged to force the clamping member toward the clamping face, and a screw trunnioned on a horizontal axis in the clamping lever and engaging the clamping member, said clamping member having a plurality of seats in its surface so arranged that one of them will receive the end of the screw, in any adjustment of the clamping member, by virtue of the trunnion mounting of the screw.

8. In a wood heel turning machine, a jack having a clamping face arranged to receive the heel-seat surface of a heel blank, a pivotally mounted clamping member arranged to engage the toplift surface of the blank, said clamping member being adjustable longitudinally of the heel blank, a clamping lever arranged to force the clamping

member toward the clamping face, and a screw trunnioned in the clamping lever on an axis perpendicular to the longitudinal axis of the heel blank and engaging the 5 clamping member, said second-named clamping member having a plurality of seats in its surface one of which may be selected to receive the end of the screw, without undue rotation of the screw in its trunnion bearing. ¹⁰

In testimony whereof I have signed my name to this specification.

WALTER W. BRADBURY.
